UNITED STATES PATENT OFFICE

133,975

DESIGN FOR A PLAQUE OR SIMILAR ARTICLE

Elmore Adams, Sr., Los Angeles, Calif.

Application April 10, 1942, Serial No. 106,518

Term of patent 3½ years

To all whom it may concern:

Be it known that I, Elmore Adams, Sr., a citizen of the United States of America, residing at Los Angeles, in the county of Los Angeles and State of California, have invented a new, original, and ornamental Design for a Plaque or Similar Article, of which the following is a specification, reference being had to the accompanying drawing, forming part thereof, wherein:

I claim:

The ornamental design for a plaque or similar article, as shown.

ELMORE ADAMS, SR.
